UNITED STATES PATENT OFFICE.

WILLIAM HOWARD BUNKER, OF LISLE, ONTARIO, CANADA.

COMPRESSOR FOR GAS ENGINES.

Application filed October 7, 1920. Serial No. 415,337.

My invention relates to improvements in fluid compressors, and the object of the invention is to provide a storage chamber for a gaseous mixture used as the motive power for combustion engines and hereinafter referred to as the mixture, and air operated means for compressing such mixture in the storage chamber and maintaining the pressure as the volume of the mixture decreases as it is drawn off from the storage chamber to the point of utilization, and it consists essentially of a main cylinder, a piston operating therein, a suitably operated piston rod for such piston, a storage cylinder, a piston operating in the storage cylinder, non-return means whereby mixture is drawn in to the main cylinder by the movement of the main piston in one direction, non-return means whereby such mixture is forced into the storage cylinder against the front face of the piston thereof by the movement of the main piston in the opposite direction whereby the piston of the storage cylinder is carried in one direction, automatic means operated by the piston of the storage cylinder when at the limit of its movement for shutting off the aforesaid mixture supply to the main cylinder and simultaneously opening an air supply to the opposite end of the main cylinder whereby the continued movement of the main piston forces the air into the opposite end of the storage cylinder to bear and produce pressure against the rear or opposite side of the storage cylinder piston, to hold in compression the mixture located in the storage chamber in front of the storage cylinder piston and a safety valve for the storage cylinder adapted to be set to control the amount of pressure produced in the storage cylinder by the air so as to produce and maintain the pressure on the mixture as the supply of the mixture in the storage chamber is decreased by being drawn off to the point of utilization, as hereafter more particularly explained by the following specification.

Fig. 1 is a side elevation of my compressor.

Fig. 2 is a similar view to Fig. 1 taken at the opposite side of the compressor.

Fig. 3 is an enlarged sectional plan taken through Fig. 1 on line 12—12.

Fig. 4 is a plan view of the compressor.

Fig. 5 is an end elevation of the compressor looking from the left hand end, as indicated in Fig. 1.

Fig. 6 is an end elevation of the compres-

sor, looking from the opposite end to that indicated in Fig. 5.

Fig. 7 is a diagrammatic plan view showing the connection of the compressor and a rotary engine, the operating parts for the sake of clearness being removed from the compressor.

Fig. 8 is a detail view showing the driving connection between the main shaft of the engine and the compressor piston rod. Fig. 9 is a sectional detail of a portion of the trip control mechanism located at the left hand end of the compressor. Fig. 10 is a perspective detail of one of the cam plates.

In the drawings like characters of reference indicate corresponding parts in each figure.

The main portion of the body of my compressor comprises a lower cylinder 81 and an upper cylinder 82. 83 is a piston operating within the cylinder 81. 84 is a piston operating within the cylinder 82 and dividing the cylinder 82 into two chambers, into one of which the mixture is fed to be held under pressure and into the other of which at the other side of the piston 84, air as a pressure maintaining fluid is fed.

85 is the piston rod of the piston 83, such piston rod passing through one end of the cylinder 81 and through a suitable bushing. The piston rod 85 is driven from the main shaft 13 of the engine by means which I will now describe.

86 is a bearing standard or suitable support located between the compressor and the engine. 87 is a lever mounted at 88 upon such support and provided at one end with a longitudinal slot 89.

90 is a link pivotally connected at 91 to 95 the piston rod 85 and pivotally connected at the opposite end at 92 to the lever 87.

93 is a push rod slidably held in suitable stationary bearings 94 and 95 and provided with an upwardly extending pin 96 100 extending into the slot 89.

97 is a bracket carried by the engine. 98 is a pinion secured to the shaft 13 of the engine.

99 is a gear mounted upon the bracket 97 105 and meshing with the pinion 98.

100 is a pinion carried by the gear 99 and meshing with the gear 101 carried by the outer end of the bracket 97.

102 is a crank pin carried by the gear 101. 110 103 is a pitman rod carried at one end upon the pin 102 and hingedly connected at its

opposite end to the push rod 93 at 104. By this means it will be seen that the piston rod 85 is reciprocated and the piston 83 reciprocated within the cylinder 81.

105 is a mixture supply pipe forming an inlet for the mixture into the cylinder 81, the piston 83 preventing the passage of such mixture past the same into the space formed by the cylinder 81 at the opposite side or rear of the piston.

106 is a non-return valve located in the pipe 105.

107 is a pipe connecting the cylinder 81 with the cylinder 82.

15 The pipe 107 is provided with a non-return valve 108.

109 is a pipe through which the mixture is discharged, such pipe also being provided with a non-return valve 110 preventing the return of the discharged mixture into the cylinder 82.

111 is a piston rod for operating the piston 84.

112 and 113 are flanges extending outward from the upper cylinder 82 and forming a guiding groove 114.

115 is a slide bar slidable within the guiding groove 114 and provided at its right hand end with an inward extension 116 terminating in a sleeve-like portion 117 in which the outer end of the piston rod 111 is secured.

118 is a cam bar which is carried by the slide bar 115 and is provided with an inclined inner end 119 for a purpose which will hereafter appear.

120 is a curved arm carried by the cylinder 81.

The arm 120 swings upon the pin 121 carried in a bracket 122, and is provided at its upper end with an inwardly curved portion 123 provided with jaws 124 in which is journalled a friction roller 125 which normally bears against the cam bar 118.

45 The lower end of the arm 120 is provided with an extension 126 which is swung upon the pin 127, and is provided with a tail piece 128 bearing against the outer edge of the arm 120. The extension piece is held in this position by means of a spring 129 which is wound around the pin 127 and bears at one end against the inner edge of the arm 120 and at its outer end against the pin 130 carried in proximity to the outer end of the extension piece 126.

55 The free end of the extension piece 126 is provided with an enlargement 131 for a purpose which will hereinafter appear. 132 is a projection extending from the piston rod 85. 133 is a lever which is pivoted on the head of the cylinder 81 at 134, the inner end of the lever extending over the piston rod 85 so as to oppose the projection 132. 135 is a slide bar carried in guiding loops 136 and 137.

60 65 The outer end of the slide bar 135 is

hingedly connected at 138 to the outer end of the lever 133. 139 is a portion extending upwardly from the slide bar 135 and on which is carried a wedge piece 140. 141 is a locking lever which is hingedly mounted 70 intermediately of its length as at 142 on the cylinder 81. The locking lever 141 is provided at its inner end with a slightly out-turned portion 143 against which the wedge piece 140 is carried in order to impart a 75 swinging action to the locking lever 141. The opposite end of the locking lever 141 is provided with an out-turned portion 144 for a purpose which will hereinafter appear. 145 is a lever pivotally carried at one end 80 upon the opposite end of the cylinder 81. The lever 145 extends from its support across the centre of the cylinder 81 to the outer periphery thereof. 146 is a slide bar held in loop supports 147 and 148. The 85 outer end of the slide bar 148 is hingedly connected at 149 to the lever 145. 150 are guiding loops located in vertical alignment and carried by the cylinders 81 and 82. 151 is a push bar extending through the guiding loops 150 so as to have free vertical movement therein. 152 is a lever pivoted at 153 and provided at its inner end with a longitudinal slot 154. 155 is a pin extending from the push bar 151 through the slot 90 154. The opposite or outer end of the lever 152 is provided with a roller 156. 157 is a block carried by the slide bar 115. The block 157 is provided with an inclined upper face with which the roller 156 engages. 100 The lower end of the push bar 151 is provided with a wedge shaped enlargement 158 located in proximity to its lower end. The head of the cylinder 81 carrying the lever 145 is provided with a central orifice 159 105 (see Fig. 9) in which is slidably held a plug 160 having heads 161 and 162. The wedge piece 158 is designed to be forced downwardly between the head 161 and the lever 145. The inner end of the slide bar 110 146 is provided with an upward extension 163 provided with a wedge shaped end 164. 165 is a lever pivoted at 166 and provided at its inner end with a slightly out-turned portion 167 contacting with the incline of 115 the wedge piece 164 and at its opposite end with an out-turned locking extension 168. The heads of the cylinder 81 are provided with cross ribbed enlargements 169 and 170 provided with longitudinal bores 171 and 172. 173 and 174 are rods slidable within the bores 171 and 172. The rods 173 and 174 are provided with diametric orifices 175 and 176 which are adapted to be brought alternately in and out of alignment with the 120 aligned orifices 177 and 178 located at one end of the cylinder and orifices 179 and 180 located at the opposite end of the cylinder. 181 is a lever swung intermediately of its 125 length upon a pin 182 carried by the cyl- 130

inder 181 and pivotally connected at each end of the rods 173 and 174 at 183 and 184.

It will thus be seen that when one of the rods 173 or 174 is moved in one direction, 5 the other of the rods 173 or 174 is moved in the opposite direction.

It will be understood that during the compression stroke of the piston 83 it is necessary that the head of the cylinder opposing 10 the piston as it makes this stroke is absolutely closed, and it is also necessary that an opening be made in the opposing head of the cylinder in order to destroy the vacuum produced by the stroke of the piston within the 15 cylinder which not only eliminates the compression of air and the retarding of the return stroke of the piston 83, but also prevents the opening of the corresponding inlet valve 106 or 208 and drawing in of mixture at one end of the cylinder 81 and air at the opposite end. In order to accomplish 20 this I have provided the rods 173 and 174 with the orifices 175 and 176 which are brought into alignment with orifices in the 25 head behind the piston when pumping of the mixture at one end of the cylinder 81 or when pumping of the air at the opposite end of the cylinder 81 by repeated strokes of the 30 piston into corresponding end of the storage cylinder 82.

I will now describe means by which the rods 173 and 174 are moved to produce this result. 185 and 186 are swinging sectors mounted upon pins 187 and 188 carried by 35 brackets 189 and 190. The sectors 185 and 186 are provided with tail pieces connected by tension springs 191 and 192 to pins 193 and 194 carried by the cylinder 81. The inner faces of the sectors 185 and 186 are provided 40 with arc shaped ribs 195 and 196 the inner faces of which incline inwardly towards their inner ends and against which inclined faces the opposing ends of the rods 173 and 174 bear. The inner faces of the 45 sectors 185 and 186 are also provided with arc shaped ribs 197 and 198 the inner faces of which incline inwardly towards their outer end and are so located that when either sector is swung to its upward position 50 the outer end of the inclined ribs are engaged with the out-turned ends of the levers 141 and 165. The levers 141 and 165 are forced out into this position by means of the 55 springs 199 and 200. 201 and 202 are compression springs adapted to return the push rods 135 and 146 to their normal position. 203 is a pipe for conveying fluid when compressed to the point of utilization, the pipe 60 and 206 being provided with branches 204, 205 and 206 leading to orifices 79. 207 is an inlet for compressing fluid such as air, provided with a suitable check valve 208. 209 is a pipe located at the opposite end of the cylinder to the pipe 107 and connecting the 65 cylinders 81 and 82 together. The pipe

209 is provided with a non-return valve 210.

211 is a pin carried by the sector 185 and 212 is a pin carried by the sector 186. 213 is a swinging depending arm carried by the slide bar 115 and formed with the shoulder 70 214 which engages with the lower face of the slide bar 115 preventing its swinging movement towards the compressing fluid inlet end 207 of the cylinder 81. 215 is an arm similar to the arm 213 but set in an opposite direction to prevent its swinging movement towards the inlet 105 for the combustible mixture into the cylinder 81. 75

In the position of the parts shown in Figs. 1 to 6 of the drawing, the combustible mixture has been forced by the piston 83 into the reservoir ready for feeding to the engine. As the piston 83 is reciprocated within the cylinder 81, the combustible mixture is drawn through the inlet 105 and past the 80 check valve 106 into the cylinder 81.

It will be noted that the valve rod 174 in Fig. 3 is in the closed position, rendering the left hand end of the cylinder active. As the piston 83 travels from left to right suction 90 is produced in the left hand end of the cylinder 81 drawing the valve 106 open and the mixture through the pipe 105 into the left hand end of the cylinder. It will also be noted that the valve rod 173 is in the open 95 position allowing for escape of air during the movement of the piston 83 to the right. As the piston 83 returns to the left no suction is produced at the right hand end of the cylinder 81, the orifices 178, 175 and 177 being in a line, and therefore rendering the right hand end of the cylinder 81 inactive 100 so that air is not drawn into the right hand end of the cylinder 81 through the pipe 207 during the pumping of the mixture at the 105 left hand end of the cylinder 81.

By the return movement of the piston 83, the valve rod 174 remaining in the closed position, the mixture is forced through the pipe 107 past the non-return valve 108 110 into the corresponding end of the storage cylinder 82 and against the left hand face of the piston 84, gradually forcing such piston from left to right by repeated strokes of the piston 83. As has been before described the 115 slide bar 115 is rigidly connected to the piston rod 111 on which the piston 84 is carried, and therefore as the piston 84 is forced in the direction above described the slide bar 115 is carried with it and also the cam bar 120 120 against which the upper end of the swinging arm 120 bears.

When the piston 84 has been driven to its final position the cylinder 82 to the right of the piston 84 (see Fig. 2), is full of mixture. The inclined portion 119 of the cam bar 118 then passes the upper end of the swinging arm 120, allowing the lower end of such swinging arm to drop into contact with the piston rod 85 and into position in 130

the path of the projection 132. As soon as this is accomplished, and by the next forward movement of the piston rod 85, the projection 132 engages the lower end of the arm 120 formed by the portion 131 carried by the spring held extension 126. The projection 132 engages this portion forcing it against spring pressure against the lever 133, which is thereby swung on its pivot, drawing the slide bar 135 in the direction of arrow, (see Fig. 1). The wedge portion 140 being part of the slide bar 135 is carried into engagement with the inner end of the lever 141, tilting it at its pivot against the pressure of the spring 199 and carrying its out-turned end out of engagement with the end of the cam rib 197, thereby freeing the sector 185 so that it is swung downward by the tension of the spring 191. By the downward swing of the sector 185, the cam rib 195 is carried in contact with the opposing end of the valve rod 173 which is thereby forced longitudinally, carrying the orifice 175 out of alignment with the orifices 177 and 178. At the same time through the lever 181 the slide bar 174 is carried in the opposite direction, carrying the orifice 176 into alignment with the orifice 179 and 180, thus rendering the left hand end of the cylinder 81 as shown in Figure 3 inactive and the right hand end active. When the mechanism is set in this position atmospheric air is free to enter the cylinder 81 at the end corresponding to the mixture inlet 105, therefore breaking any vacuum which might be formed so that the piston will not draw the check valve 106 off its seat and allow the mixture to enter. After this has taken place, the next stroke of the piston 83 as it travels from the mixture inlet end is an idle or non-working movement, drawing no mixture as heretofore, but upon its return movement air is drawn through the inlet 207 past the non-return valve 208 into the cylinder 81, then as the piston 83 again passes towards the air inlet end the indrawn air is forced up into the cylinder 82. This operation continues, forcing the piston 84 in the opposite direction, that is, referring to Fig. 2 towards the right hand end of the cylinder 82, compressing the charge of mixture on the right hand side of the piston 84.

It will be noted that the pipe 203 is provided with a pressure controlling valve 216 which may be of any type which is commonly in use. I do not describe this in detail as it is a valve which is a standard valve which can be obtained anywhere upon the market.

As the air is forced into the cylinder 82 it produces a gradually increased compression up to a maximum upon the mixture contained in the cylinder 82 at the opposite side of the piston 84, which maximum is controlled by the set of the valve 216. This

pressure is exerted upon the mixture in the cylinder 82 at the opposite side of the piston 84. If the air pressure rises above this maximum, it is released through the valve 216. As the mixture is drawn off through the pipe 203 to the point of utilization and its volume decreases in the cylinder 82 at the right of the piston 84, the volume of air increases on the opposite side of the piston so that by means of the valve 216 the maximum pressure is exerted upon the mixture and such maximum pressure maintained.

It will thus be seen the mixture is pumped from one end of the cylinder 81 into the corresponding end of the cylinder 82 and when the storage cylinder 82 is filled to capacity mechanism is actuated by the piston 84 to stop such pumping operation and start pumping operation at the opposite end of the cylinder 81 to pump air into the opposite end of the cylinder 82 to exert a predetermined pressure upon the mixture controlled by the valve 216.

It will thus be seen that a constant equal pressure is exerted upon the mixture so that it will always be fed to the engine at the same pressure no matter how much mixture is held in reserve within the cylinder 82 at the right of the piston 84. As the piston 84 is carried in the reverse direction during the feeding of the mixture from the cylinder 81, to the point of consumption such as an engine 5, the slide bar 115 is carried in the reverse direction to that previously described, carrying the swinging arm 213 into engagement with the pin 211, gradually forcing the sector upward and inward towards the position shown in the drawing. It will be understood that when the sector 185 is released it swings outward and downward carrying the pin 211 upward into the path of the arm 213. When the piston rod 111 moves outward the arm 213 is carried by the bar 118 in the same direction, the lower end striking the pin 211 and swinging on its pivot to pass the same. When the piston rod 111 returns, the arm 213 engages the outer side of the pin and is held rigid by the angular portion of the arm engaging beneath the slide bar 115 so that when such arm engages the pin 211 it forces the sector 185 back to its normal position. Upon the slide bar 115 completing its return movement, the wedge piece 157 is carried beneath the outer end of the lever 152, swinging the inner end thereof downward and forcing the wedge portion 158 between the lever 145 and the plug 160, thereby tending to force the lever 145 outward and the plug 160 inward. When this is effected, the piston 83 at the end of its movement towards the mixture inlet end of the cylinder 81, is carried against the plug 60, forcing it outward and thereby drawing the slide bar 146 and wedge portion 164 within the inner end of the lever 165, there-

by forcing the lever against the pressure of the spring 200 out of engagement with the end of the cam rib 168, thereby freeing the sector 186 which is then carried downward 5 by the spring 192. The cam rib 196 during this movement contacts with the opposing end of the valve rod 174, forcing it in the opposite direction to that previously described, and thereby again reversing the position of the valve rods 174 and 173.

As soon as this operation is complete, the combustible mixture is again drawn into the cylinder 81 to be stored in the cylinder 82. During the next storing operation of the 15 combustible mixture the depending arm 215 engages the pin 212 carrying the sector 186 back to its normal position to be locked in such position by the lever 165.

What I claim as my invention is:

- 20 1. A gas compressor comprising a main gas compressing cylinder and a piston reciprocating within the cylinder, a gas inlet, a gas reservoir, a gas outlet connecting the main cylinder and reservoir, a non-return 25 valve from the gas outlet, and means actuated by the reciprocation of the piston within the main cylinder for producing a constant air pressure against the charge of gas within the reservoir.
- 30 2. A compressor, comprising a gas compressing cylinder, a gas reservoir, a gas inlet at one end of the compressing cylinder and an air inlet at the opposite end, a non-return valve for controlling each inlet, a 35 valve controlled vent located at each end of the compressor cylinder, pipes connecting each end of the compressing cylinder at each end of the reservoir provided with non-return valves, a piston within the reservoir 40 against one face of which the gas is fed from the compressor cylinder and against the opposite face of which air is fed, means operated by the movement of the reservoir piston as it reaches each end of its stroke for 45 closing the aforesaid vent at the corresponding end and opening the vent at the opposite end of the compressor cylinder, an outlet pipe for feeding the air from the reservoir provided with a pressure control valve.
- 50 3. A compressor, comprising a compressing cylinder having a gas inlet at one end and an air inlet at the opposite end, a piston coacting with the compressor, a reservoir cylinder, a piston coacting with the reservoir, a vent at each end of the compressor cylinder, a slide valve controlling each port, a lever pivoted intermediately of its length and pivotally connected at its ends to the 55 slide valves, a tripable cam means operating against the opposite end of each slide valve, means operated by the piston of the reservoir as it reaches each end of its stroke

for tripping one of such cam mechanisms to move the corresponding valve to the closed position and the corresponding valve at the opposite end of the cylinder to the open position, a check valve controlling pipes connecting each end of the compressor cylinder with each end of the reservoir cylinder, and a valve controlled air discharge pipe leading from the reservoir. 65 70 75

4. A compressor, comprising a compressing cylinder having a gas inlet at one end and an air inlet at the opposite end, a piston coacting with the compressor, a reservoir cylinder, a piston coacting with the reservoir, a vent at each end of the compressor cylinder, a slide valve controlling each vent, a lever pivoted intermediately of its length and pivotally connected at its ends to the 80 slide valves, a tripable cam means operating against the opposite end of each slide valve, means operated by the piston of the reservoir as it reaches each end of its stroke for tripping one of such cam mechanisms 85 to move the corresponding valve to the closed position and the corresponding valve at the opposite end of the cylinder to the open position, check valve controlled pipes connecting each end of the compressor cylinder with each end of the reservoir cylinder, and valve controlled discharge pipes leading from the reservoir, and means for returning the cam mechanisms to their normal position operated by the reverse movement of the piston of the reservoir. 90 95

5. In a compressor, the combination with the compressor cylinder, of an air inlet pipe at one end of the compressor cylinder, and a gas inlet pipe at the opposite end, a reservoir cylinder, a piston operating within the reservoir cylinder, non-return valve controlled pipes connecting the ends of the compressor cylinder and reservoir cylinder together, a vent at each end of the compressor cylinder and slide valves controlling said each vent, a piston rod for the reservoir piston, a cam bar slidable in guide ways and connected to the piston rod of the reservoir and tripping mechanism, a swinging arm bearing at one end against the cam bar, means coacting with the compressor piston rod for tripping mechanism at one end of the compressor cylinder upon the release of the swinging bar, means operated by the trip mechanism for moving the slide valve at the corresponding end of the compressor cylinder, and tripping mechanism at the opposite end of the compressor cylinder operated by the compressor piston as it reaches the end of its stroke whereby the slide valve at the opposite end of the cylinder is operated. 100 105 110 115 120

WILLIAM HOWARD BUNKER.
